Patented Dec. 9, 1919.

Alice H. Allen, Inventor

UNITED STATES PATENT OFFICE.

ALICE H. ALLEN, OF SPRINGFIELD, OHIO.

DESIGN FOR A FLAG OR THE LIKE.

54,233.

Specification for Design.

Patented Dec. 9, 1919.

Application filed December 12, 1918. Serial No. 266,499. Term of patent 14 years.

To all whom it may concern:

Be it known that I, ALICE H. ALLEN, a citizen of the United States, residing at Springfield, in the county of Clark and State of Ohio, have invented a new, original, and ornamental Design for Flags or the like.

The figure is a view of a flag, showing my new design.

I claim:

The ornamental design for a flag or the like, as shown.

ALICE H. ALLEN.
